UNITED STATES PATENT OFFICE.

JAMES L. ABERNETHY, OF PARK RIDGE, AND LEONARD E. MUMBOWER, OF CHICAGO,
ILLINOIS.

WRENCH.

Application filed April 5, 1926. Serial No. 99,709.

This invention relates to a wrench of that type possessing a rotatable and multiple socket member.

It is an object of this invention to provide a novel means for securely locking the rotatable socket member in its adjusted position, said means being susceptible of being readily manipulated while the wrench is in position for operation. That is, when it is in a position to be applied to a nut or bolt or the like.

This invention comprises the novel structure and combination of parts hereinafter described and more particularly pointed out and defined in the appended claims.

In the accompanying drawings which illustrate a preferred embodiment of this invention and in which similar reference numerals refer to similar features in the different views,

On the drawings:

Figure 1 is an elevational view of a wrench embodying this invention.

Figure 2 is an enlarged part sectional and part elevational view of the wrench.

Figure 3 is an enlarged sectional view upon the line III—III of Figure 1.

Figure 4 is an elevational view of the multiple socket member.

As shown on the drawings:

In referring to the drawings it will be noted that we have illustrated a wrench comprising a handle 1 having a pawl 2. The handle 1 is rotatably mounted upon a stem 3 having ratchet teeth 4 adapted to be engaged by the pawl 2 when the handle is rotated in the proper direction. The stem 3 is bifurcated at its lower end forming a sort of fork. In this bifurcation, the multiple socket member 5 is rotatably mounted upon a shaft 6 fastened in the wings of the bifurcation. One face of the socket member is in the form of a disk 5a having notches or slots

7 for receiving the end 8 of a detent member 9 which is pivoted intermediate its ends 45 upon a pivot member 10 which bridges a suitable gap or slot 11 in a wing of the bifurcated end of the stem. A spring 12 is positioned between the operating end of the detent 9 and the stem 3 with the inner 50 end of the spring being confined in a suitable socket 13 formed in the stem.

It will be appreciated that when in use, the operator usually grasps the stem 3 for adjusting the wrench on the part to be 55 turned. Consequently it will be very convenient to place the thumb on the detent 9 for operating it against the spring and withdrawing the locking end from the slot 7 in the face of the socket member allowing 60 the latter to be rotated to bring the proper socket into position.

We are aware that many changes may be made and numerous details of construction may be varied through a wide range without departing from the principles of this invention, and we therefore do not purpose limiting the patent granted hereon otherwise than necessitated by the prior art.

We claim as our invention:

In a wrench, a stem having spaced wing plates, a member having a plurality of sockets rotatably mounted between said wing plates, said member having one of its faces provided with notches, a detent member having an integral lug adapted for engaging said notches and pivoted intermediate its ends to one of said wing plates, said wing plate having a slot for accommodating said detent member, and a spring for normally 75 maintaining said detent member in locking position.

In testimony whereof, we have hereunto subscribed our names.

JAMES L. ABERNETHY.
LEONARD E. MUMBOWER.
